UNITED STATES PATENT OFFICE.

RALPH BAGGALY, OF PITTSBURG, PENNSYLVANIA.

APPARATUS FOR MINING.

No. 802,349.

Specification of Letters Patent.

Patented Oct. 17, 1905.

Original application filed May 25, 1904, Serial No. 209,622. Divided and this application filed December 5, 1904. Serial No. 235,417.

To all whom it may concern:

Be it known that I, RALPH BAGGALY, of Pittsburgh, in the county of Allegheny, in the State of Pennsylvania, have invented new and useful Apparatus for Mining, of which the following is a full, clear, and exact description, reference being had to the accompanying drawing.

This application is a division of my former application filed May 25, 1904, Serial No. 209,622, for a "method of mining."

In the drawing the figure represents a cross-section of an upraise or manway on a mineral-vein from the main level of the underground workings.

The object of my invention is to cheapen the cost of producing ore from mineral-veins in shaft mines in districts to which the apparatus is applicable.

Before actual mining commences I sink working shafts, preferably to a great depth—say to two thousand feet—on which level all subsequent working is conducted until after all the mineral values have been extracted from all the veins that lie above that level. In lieu of timbering I preferably use double-screw jacks 2 and timber blocks to temporarily support the ore roof of the workings during mining operations, and these devices, while expensive in first cost, may be used continuously. As underground developments progress in this method of mining exact surveys and maps are continually maintained, which accurately represent the location of such underground workings, and by means of these maps I from time to time drill holes 3—say from four to ten inches in diameter—from the surface down to such point or points underground and to such level or levels underground where ore stoping is in progress. When such a hole has been thus drilled from the surface down to a point where stoping is in progress, I preferably line it with a light metal tube or casing 4, and thereafter I deliver the filling material through this tube from the surface by gravity to the level on which mining-work is in progress. This material may consist of sand, gravel, clay or dirt of any kind, crushed rock, and similar substances; but my preference is to utilize granulated or cracked slag, because in this manner I may be enabled to remove the ores continuously from the underground workings, extract all of the mineral values from them with great economy, granulate the resulting slags, and thereafter restore it in vitrified form to

the underground workings. It is a well-known fact in the Butte district, as well as in many other sections where smelting operations are conducted, that land for use as slag-dumps is expensive and that the handling and the disposal of waste slags in present smelter practice are costly. The uses of the tubes 4 from the surface to the underground workings are twofold. They may be used for the delivery of filling material into the mine-workings, and their manner of use for this purpose must always be governed by the material that is used for filling. For instance, if broken rock is used the tubes should first be filled with sand or with granulated slag extending from the hopper 5, that stands immediately under its end in the underground workings, up to the receiving-hopper at its upper end on the surface. Thereafter crushed rock, cracked slag, and such material may be fed into the upper hopper, because as the material is drawn out below in the underground working into a car 6, a carload at a time, from the gate 7 in the hopper at the bottom of the tube all of this material is thus forced to move slowly and gradually downward into the hopper at the bottom. In this way crushed rock, cracked slag, &c., may be delivered into the hopper below without material injury to the tube or to the hopper beyond the ordinary wear and tear incident to such sliding material. If sand or granulated slag is used as filling, it may be delivered into the upper hopper a shovelful at a time, if desired, because in its flight to the hopper below such material is incapable of injuring either the pipe or the bottom hopper. I prefer the latter method of procedure because this enables me to leave all of these tubes in a given drift open to the surface. This has the effect of thoroughly ventilating all parts of the stopes where mining operations are in progress, and any one familiar with the difficulties of securing good ventilation in stopes and in upraises will appreciate the importance of this feature. As mining-work progresses and as the regular dip of the vein is followed upward and as the ore contained in the vein is regularly and systematically mined out from wall to wall it will be apparent that in time the filling underfoot will ultimately reach the point where the lower end of the tube will be covered within the underground workings. When this point is reached, the tube is extracted by machinery from above for reuse,

and this hole 3 is then filled solidly with granulated slag from the surface down to the mine-workings as a means of preventing possible accident. A new and similar hole 3' is 5 drilled to again intercept the underground workings, so located as to be as near the foot-wall as possible in order that its usefulness may thus be prolonged. Each drift on each side of the main cross-cut tunnel is thus 10 operated on a similar system. The ore from each drift is dumped from tram-cars as mined into a metallic chute or chutes shown in the drawings, which are preferably located every two hundred feet on the drift continuously 15 as the mining-work progresses upward, and such ore is continuously withdrawn from the hopper or hoppers at the bottom of such chute below by the carman in the drift. When the drift has been worked out and all 20 of the mineral has thus been extracted from the vein completely to its top surface or outcrop or as close to the outcrop as the surrounding conditions render it safe to carry the mining operations, filling material is then 25 packed solidly from the end of such drift at the utmost limit of the property-line, and such back filling is continued forward toward the main cross-cut tunnel. The entrance to the drift-tunnel to this exhausted and abandoned drift is then walled up at its junction-line with the main cross-cut tunnel, and thereafter filling material from above is sent 30 down through a tube 4, that has been suitably located for the purpose, preferably accompanied with water, so that in this manner it will fill up solidly the last manway and all 35 remaining spaces in the abandoned workings. The last tube from the surface into the underground workings will be quite short, inasmuch as the extraction of mineral in the vein has presumably been carried to a point 40 near the surface. This tube is purposely located in such position as to facilitate the final filling of the last manway and of the underground workings solidly up to the roof. If 45 desired, this last tube may be left in position for a month or two in order that additional filling material may be delivered through it into the underground workings, preferably 50 accompanied with water, in case any settling of the filling material in the underground workings should become apparent.

In the drawing I show the ore in a drift extracted from the floor-level of the main 55 cross-cut tunnel up to the floor on which the screw-jacks, tramway, and the filling-material hopper are resting. This vacant space has been subsequently filled with granulated slag up to that level. The lower portion of the

upraise is built, preferably, of vitrified brick, 60 and this is filled on its outside surfaces solidly with granulated slag to each wall of the vein fissure after the ore has been extracted.

I call especial attention to my method of delivering filling material from the surface 65 of the ground into the mine-workings of each separate drift and onto the various levels as the mining-work progresses. It will be noted in the drawings that the main tube or chute, as shown, has been located primarily at its 70 lower end near to the foot-wall in order that it may be utilized as long as possible as the mining-work progresses upward. The drawing shows the lower end of a second tube as just entering the ore-body. Its location is 75 such that as the mineral is steadily and continuously extracted upward from the vein and when the available limit of the tube shown as in use has been reached the mine-workings will already have penetrated the area 80 that can be served by the second tube. It will be understood that as the mine-workings progress upward—say, for instance, to the point where the lower end of the first tube, as shown, would be closed by the filling material underfoot—this tube or casing is either pulled up from the surface of the ground to a corresponding extent or it may be unscrewed or cut off within the mine-workings in the event of its becoming bound in the rock from 85 any cause.

Variations will doubtless suggest themselves in the details of the apparatus without departing from the spirit of my invention, since

What I claim is—

1. Apparatus for mining comprising a passage other than the mine-shaft extending from the surface of the ground, and a tube therein for the passage of filling material; substantially as described.

2. Apparatus for mining comprising a passage other than the mine-shaft extending from the surface of the ground, a tube therein for the passage of filling material, and a hopper at the bottom of the tube; substantially as described.

3. Apparatus for mining comprising a passage other than the mine-shaft extending from the surface of the ground, a tube therein for the passage of filling material, and a gated receiving-hopper beneath the tube; substantially as described.

In testimony whereof I have hereunto set my hand.

RALPH BAGGLEY.
